INCORPORATED, OF NEW YORK, N. Y., A CORPORATION OF NEW YORK.

MACHINE-SWITCHING TELEPHONE-EXCHANGE SYSTEM.

1,251,544.

Specification of Letters Patent.

Patented Jan. 1, 1918.

Application filed April 26, 1916. Serial No. 93,639.

To all whom it may concern:

Be it known that I, ALBEN E. LUNDELL, a citizen of the United States, residing at New York, in the county of Bronx and 5 State of New York, have invented certain new and useful Improvements in Machine-Switching Telephone-Exchange Systems, of which the following is a full, clear, concise, and exact description.

- 10 This invention relates to telephone exchange systems employing machine switching, and particularly to systems wherein idle line finders are associated with calling lines by an advanced starter wire. In such systems there is necessarily an interval during 15 which a call may be delayed, this interval occurring while the starter wire is being advanced to the next idle finder after the initiation of a call.
- 20 The object of this invention is to reduce this interval, and the novelty consists in a circuit arrangement wherein, in a finder having a primary and secondary movement, a circuit arrangement is provided for extending the starter wire to the next idle finder upon the termination of the primary 25 movement of such finder in seeking a calling line, instead of upon the termination of the secondary movement of such finder.
- 30 Referring to the drawing, which shows only so much of a telephone exchange system as is necessary for a comprehension of the invention, the lines terminate in multiples 128, 129 of a number of automatic finder 35 switches dependent on the traffic. Each line is also provided in the finders with test multiples 110, and with the usual line and cut-off relays 100, 102. The finder brushes are designated 125, 126, 127 and are adapted 40 to be given a primary movement by a magnet 119 to position the same in operative relation to the group of multiples containing the calling line and a secondary movement by a magnet 133 to pick out the calling line multiples in the group.
- 45 The invention will be more clearly understood by tracing the operations involved in setting up a connection.
- Upon the removal of the receiver by the 50 subscriber at substation A, line relay 100 is energized over the following circuit: free pole of battery, left winding of relay 100, conductor 101, left armature and back contact of cut-off relay 102, conductor 103, line conductor 104, telephonic apparatus at sub- 55 station A, line conductor 105, conductor 106, right armature and back contact of relay 102, conductor 107, right winding of relay 100 to ground. Relay 100, in attracting its left armature, closes the following shunt path 60 about the cut-off relay 102 to test multiples 110 of the calling line: free pole of battery, resistance 108, left armature and front contact of relay 100, conductors 109 and 135. The closure of this shunt path about the cut- 65 off relay 102 causes a calling condition to be placed upon the test multiples 110 in the finders in which line A appears. Relay 100, in attracting its right armature, closes the following circuit for a starting relay 114: 70 free pole of battery, resistance 112, right armature and front contact of relay 100, conductor 113, relay 114 to ground. The closure of this circuit also places a calling condition upon the multiple commutator 75 segments 111 of the group of lines to which substation A belongs. Relay 114, in attracting its armature, closes the following circuit for a relay 115: free pole of battery, 80 armature and front contact of relay 114, conductor 116, finder side-switch arm 1 and its first contact, conductor 117, left winding of relay 115, conductor 118 to ground at the armature and back contact of the primary stepping magnet 119 of the finder. Relay 115, 85 in attracting its armature, closes the circuit of magnet 119, and the magnet 119, in attracting its armature, opens the circuit of relay 115. Thus the finder brush shaft 120 is given a primary movement in search of 90 the calling group. When the brush 121, which rotates with the brush shaft 120, encounters multiple segment 111 of the calling group, now grounded, the following circuit is closed to energize the escape magnet 122 95 of the finder side switch: free pole of battery, resistance 112, right armature and front contact of relay 100, conductor 113, segments 111, brush 121, conductor 123, arm 6 and its first contact, magnet 122, conductor 124, right winding of relay 115 to ground. The armature of magnet 119 is arranged to open the circuit through the left winding of relay 115 near the end of its stroke, and the commutator brush 121 is ar- 105 ranged to close the circuit for magnet 122 and the right winding of relay 115, before the circuit through the left winding of said relay is broken by the armature of magnet 119. Relay 115 is adapted to energize in 110

this circuit, with the result that magnet 119 is maintained energized for an instant after the last step to prevent the shaft 120 from overthrowing. The escape magnet 122 is 5 constructed to release the side switch from position to position upon its energization, and upon the closure of the circuit traced, releases the side switch into position 2. Arm 6, in moving off its first contact, de- 10 energizes escape magnet 122 and relay 115. In position 2, arm 6 shunts out relay 114, with the result that the in-starter 132 is connected to the out-starter wire 131 over arm 1 and its second contact. A call may 15 now come in from another group over the in-starter wire 132, and set the finder connected to the out-starter wire 131 in motion, while the finder shown in the drawing is making its secondary movement in search 20 of the calling line. Upon the termination of the primary movement of the finder and the release of the side switch into its second position, arm 5 closed the following circuit for the secondary stepping magnet 133 of 25 the finder, to drive the positioned brushes 125, 126, 127 over the multiples of the calling group containing those of the calling line: free pole of battery, magnet 133, its armature and back contact, arm 5 and its 30 second contact to ground. In position 2 of the side switch, arm 4 connects the escape magnet 122 to test brush 127. When the test brush 127 reaches the test multiples 110 of the calling line, upon which a calling 35 condition has been placed by the attraction of the left armature of relay 100, escape magnet 122 becomes energized and releases the side switch into position 3. Although the right winding of relay 115 is included in 40 the circuit of magnet 122 as before, it is not adapted to respond, through the resistance 108.

Arm 5, in leaving its second contact, opens the circuit of the secondary stepping magnet 133, thus stopping the finder brushes 125, 126, 127 upon the multiples of the calling line 128, 129, 110. The escape magnet 122 will not energize as brush 127 passes over multiples 110 of non-calling lines, since it 50 will not receive enough current. In position 3, arm 1 maintains the continuity of the in and out-starter wires 132, 131. Arm 4, in moving into position 3, closes the following circuit to energize the cut-off relay 102 of the 55 calling line: free pole of battery, relay 102, conductor 134, conductor 135, test multiples 110, test brush 127, conductor 136, arm 4 and its third contact to ground. Relay 102, in attracting its armatures, deenergizes the 60 line relay 100, which, in retracting its left armature, removes the calling condition from the multiples 110 of the calling line in the finders in which it appears, and in re-tracting its right armature, removes the call- 65 ing condition from the multiple commutator

segments 111 of the calling group. Arms 2 and 3, in moving into position 3, energize a relay 137 over the following circuit: free pole of battery, left winding of relay 137, conductor 138, talking conductor 139, arm 2 70 and its third contact, conductor 140, brush 125, terminal 128, conductor 104, telephonic apparatus at substation A, conductor 105, terminal 129, brush 126, arm 3 and its third contact, conductors 141, 136, right winding 75 of relay 137 to ground. Relay 137 energizes and interposes a break in the circuit of the finder release magnet 143 before the side-switch arm 5 is closed sufficiently long to permit the energization of such release 80 magnet. Relay 137, by attracting its armature, energizes a slow relay 144 over side-switch arm 5 and its third contact. Relay 144, in attracting its armature, interposes another break in the circuit of release mag- 85 net 143. The relay 137 may be the stepping relay of the first selector, or in the case of a system where the line finders merely distribute calls to idle operators, may operate a calling lamp, whereupon the operator may 90 complete the connection in any suitable manner.

Going back to that point in the operation where the escape magnet 122 released the side switch into position 2, when brush 121 95 reached grounded calling group segments 111, arm 6, in moving into position 2, shunts out relay 114, which, in retracting its armature, connects in-starter wire 132 to conductor 116, which conductor is connected 100 over arm 1 in this position, through slow relay 146 to out-starter wire 131, and from thence to relay 115 of the next idle finder. If, when relay 114 retracts its armature, the in-starter wire 132 is connected to free pole 105 of battery, a circuit is closed to start the next idle finder with which the out-starter wire 131 is associated in search of the line whose call caused such connection to battery of conductor 132. The circuit may be 110 traced as follows, assuming the finder shown to belong to the group initiating such call: free pole of battery, armature and front contact of relay 114, conductor 116, arm 1 and its third contact, slow relay 146, out-starter wire 131, in-starter wire 132 of the 115 finder shown, armature and back contact of relay 114, conductor 116, arm 1 and its second contact, slow relay 146, out-starter wire 131, in-starter wire 132 of the idle 120 finder, armature and back contact of relay 114, conductor 116, arm 1 and its first contact, conductor 117, left winding of relay 115, conductor 118, armature and back contact of the primary magnet 119 of such 125 finder to ground. The magnet 119 and relay 115 of such finder will now interact to step the shaft 120 thereof until the brush 121 reaches the segment of the calling group, whereupon the escape magnet 122 of such 130

finder will energize and release the side switch into position 2, in which position the secondary movement of the shaft will take place to drive the positioned brushes over 5 the multiples of the calling group, as already described.

The brush 121 is keyed to the shaft 120 as shown to rotate therewith. However, such brush does not partake of the vertical movement of the shaft, but remains in contact with the calling group commutator segments 111. This is necessary in order to maintain relay 114 shunted out; otherwise this relay would reenergize upon the first secondary 15 step, and disconnect the in-starter wire 132 from conductor 116 leading to the out-starter wire 131.

A slow relay 146 is provided for each finder. The function of these relays is to interpose a break in the circuit of the release magnets of the finders with which they are associated, while a finder beyond is operating over a circuit passing through side-switch arms 1 and the third contacts of such 25 finders, since if one of these intermediate finders releases during the operation of the finder being set, the side-switch arm 1 of such released finder will, in moving back to its first contact, upon the energization 30 of the associated release magnet, disrupt the stepping circuit.

What is claimed is:

1. In a telephone exchange system, the combination with telephone lines, automatic 35 line finder switches to which said lines are multiplied in groups, a starter wire for associating an idle finder with said lines, means adapted upon the initiation of a call to give said finder a primary movement to place the 40 same in operative relation to multiples of the calling group, and means for automatically giving said finder a secondary movement to connect with the calling line multiples, of means actuated upon the termination 45 of the primary movement to extend the starter wire to the next idle finder.

2. In a telephone exchange system, the combination with telephone lines, automatic line finder switches to which said lines are 50 multiplied in groups, stepping magnets for giving said finders a primary and secondary movement, a starter wire for associating an idle finder with said lines, means adapted upon the initiation of a call to operate said 55 primary stepping magnet over said starter wire, and means for operating said secondary stepping magnet automatically upon the termination of said primary movement to

cause said finder to connect with the calling line, of means actuated upon the termination 60 of the primary movement for extending the starter wire to the next idle finder.

3. In a telephone exchange system, the combination with telephone lines, automatic finder switches to which said lines are multiplied in groups, primary and secondary stepping magnets for said finders, a starter wire for associating an idle finder with said lines, and a line relay adapted upon the initiation of a call to place a calling condition 70 upon the test multiples of the calling line in such finders and upon the multiple group segments of the calling group in such finders, of a starting relay energized upon the operation of said line relay to interpose a break in 75 the incoming end of said starter wire and to operate said primary stepping magnet over a portion of said starter wire, and a brush carried by said finder adapted when the calling group segment is reached to stop the operation of said primary magnet and to de-energize said starting relay to reconnect the incoming end of said starter wire to the outgoing end thereof.

4. In a telephone exchange system, the 85 combination with telephone lines, automatic line finder switches to which said lines are multiplied in groups, side switches for controlling said finders, escape magnets therefor, primary and secondary stepping mag- 90 nets for said finders, a relay 114, a starter wire for associating an idle finder with said lines over a back contact of relay 114 and an arm of the associated side switch, a line relay adapted upon the initiation of a call to 95 place a calling condition upon the multiples of the line in the finders in which it appears and on the calling group segments in such finder and to energize relay 114 to interpose a break in the incoming end of said starter 100 wire and to operate said primary stepping magnet over a portion of said starter wire, of a brush carried by said finder adapted when the multiple calling segment is reached to shunt out said relay 114 and operate the 105 escape magnet 122 of said side switch which releases the side switch into position 2 to close the circuit of said secondary stepping magnet, said relay 114 at its back contact reconnecting the incoming section of the 110 starter wire through said side-switch arm and its second contact to the out-starter wire.

In witness whereof, I hereunto subscribe my name this 25th day of April A. D., 1916.

ALBEN E. LUNDELL.
